US0D1048144S

(12) **United States Design Patent** (10) Patent No.: **US D1,048,144 S**
(45) Date of Patent: ** Oct. 22, 2024

(54) **CAMERA**

(71) Applicant: **HANWHA TECHWIN CO., LTD.**,
Seongnam-si (KR)

(72) Inventor: **Joo Young Shin**, Seongnam-si (KR)

(73) Assignee: **HANWHA VISION CO., LTD.**,
Suwon-si (KR)

(**) Term: **15 Years**

(21) Appl. No.: **29/823,657**

(22) Filed: **Jan. 19, 2022**

(30) **Foreign Application Priority Data**

Dec. 14, 2021 (KR) 30-2021-0060141

(51) **LOC (14) Cl.** **16-01**

(52) **U.S. Cl.**

USPC **D16/203**

(57) **CLAIM**

The ornamental design for a camera as shown and described.

DESCRIPTION

FIG. 1 is a perspective view of a camera, showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The broken lines in the drawings form no part of the claimed design.

1 Claim, 7 Drawing Sheets
